UNITED STATES PATENT OFFICE.

KARL WIESER, OF BREDENEY, GERMANY, ASSIGNOR TO FRIED. KRUPP AKTIEN-
GESELLSCHAFT, OF ESSEN-ON-THE-RUHR, GERMANY.

PROJECTILE.

1,063,094.

Specification of Letters Patent.

Patented May 27, 1913.

Application filed October 28, 1909. Serial No. 525,067.

To all whom it may concern:

Be it known that I, KARL WIESER, a subject of the Emperor of Germany, and a resident of Bredeney, Germany, have invented certain new and useful Improvements in Projectiles, of which the following is a specification.

This invention relates to projectiles with arrangement for delaying the ignition of 10 the bursting charge.

Delay action devices in which a delay action composition, is introduced into the path of the igniting flame and subjected to the same immediately or through the medium 15 of a reinforcing charge, fail to accomplish their purpose when the igniting flame is extraordinarily strong, because the igniting flame in such cases, induces instantaneous explosion of the delaying substance so that 20 the delay action does not take place. A forcible action of the igniting flame such as referred to, takes place for example in armor piercing projectiles because the igniting pellet of the impact fuse, in consequence 25 of the hard impact of the projectile against the armor plate, is pierced with extraordinary force. In order to secure the sure occurrence of delay in strongly acting igniting flames, a delay action device has been 30 employed in which the delay of the ignition has been produced without the use of a retarding substance by merely compelling the igniting flame to repeatedly change its direction. But with delay action devices of 35 this kind, only delays of comparatively short duration are attainable, which under circumstances such, for example, as when shooting against comparatively strong armor plates, are not sufficient.

40 The present invention has for its purpose to provide a projectile whose bursting charge can be brought to detonation with a delay of long duration, even with strongly acting igniting flames. This purpose is attained according to the present invention, 45 by preceding the bursting charge of the projectile with a retarding substance, and by providing between this retarding substance and the space in which the igniting flame is 50 produced, an arrangement for weakening the igniting flame.

One embodiment of the invention is shown in the accompanying drawing by way of illustration.

55 In said drawing, Figure 1 is a longitudi-

nal section through the base of an armor piercing exploding shell, and Fig. 2 is a section on the line 2—2, Fig. 1.

The bolt B, which carries the fulminate pellet A is slidably mounted in the fuse 80 housing C. Secured in the fuse housing C at a suitable distance above the transport position of the bolt B is a disk E, which carries the igniting needle D. The disk E is provided with a central bore e¹ to receive the shank d¹ of the igniting needle which enters the disk. Seated against the bolt B is the check spring b¹ whose out-turned end supports the dogging ring F. The spring abuts with its upper end, the 70 disk E.

Immediately above the disk E in the fuse housing, is located an attachment piece H provided with a channel h¹. This serves for conducting the igniting flame of the fulminate pellet A to a retarding substance J. The channel h¹ takes a zigzag course and terminates in the longitudinal axis of the fuse beneath the retarding substance J. From the latter, channels h² lead to the 80 driving charge K which serves for the ignition of a detonator (not shown) lying in advance of the bursting charge of the projectile. The fuse fits in a bushing L, which is screwed into the base of the projectile 85 body M.

If the described armor piercing exploding shell impinges an armor plate, the fulminate pellet A will be driven with great violence against the igniting needle D in consequence 90 of the hard impact, so that a very forcible igniting flame results, which by its immediate effect upon the retarding substance, would produce an instantaneous explosion. But since the igniting flame, in striking 95 through the channel h¹, must repeatedly change its direction, its force will be so far reduced that it will cause but a slow burning of the retarding substance. The ignition of the bursting charge of the projectile, 100 therefore, follows with a delay corresponding to the dimensions of the retarding substance.

In order that the igniting flame may not die out in traversing the zigzag fire channel 105 of comparatively great length, there may be provided, if desired at individual places in the fire channel, small perforated powder bodies of such properties that they will also be momentarily exploded by the weakened 110

igniting flame. The fire flame of the fulminate pellet, receives such strength from these powder bodies (reinforcing powder substance) that it will act with certainty in 5 the ignition of the retarding substance J.

It will be understood that the invention is not restricted to use on armor piercing projectiles. It can be employed with like results in other forms of projectile, in which 10 the fire flame develops such force that its immediate action upon the retarding substance would have the effect of inducing instantaneouse explosion.

Having thus described my invention, what 15 I claim as new therein and desire to secure by Letters Patent is—

1. In a projectile containing a bursting charge and means for causing an igniting flame, the combination with a retarding substance 20 interposed in the path of the igniting flame, of means for weakening the igniting flame, said means being placed between the retarding substance and the place where the igniting flame is produced.

2. In a projectile containing a bursting charge and means for causing an igniting flame, the combination with a retarding substance 25 interposed in the path of the igniting flame, of means for weakening the igniting flame, said means being placed between the retarding substance and the place where the igniting flame is produced.

3. In a projectile containing a bursting charge and means for causing an igniting flame, the combination with a retarding substance 30 interposed in the path of the igniting flame, of means for weakening the igniting flame, said means being placed between the retarding substance and the place where the igniting flame is produced and comprising a circuitous channel through which the flame must pass to reach the retarding substance.

3. In a projectile containing a bursting 35 charge and means for causing an igniting flame, the combination with a retarding substance interposed in the path of the igniting flame, of means for weakening the igniting flame, said means being placed between the 40 retarding substance and the place where the igniting flame is produced, and comprising a circuitous channel through which the flame must pass to reach the retarding substance, said circuitous passage being of zig-zag 45 form which compels the igniting flame to repeatedly change its direction.

4. In a projectile containing a bursting charge and means for causing an igniting flame, the combination with a retarding substance interposed in the path of the igniting flame, of means for weakening the igniting flame, said means being placed between the 50 retarding substance and the place where the igniting flame is produced, and comprising a circuitous channel through which the flame must pass to reach the retarding substance and said circuitous passage being provided at suitable points with reinforcing powder substance.

The foregoing specification signed at Bar- 55 men, Germany, this 16th day of October, 1909.

KARL WIESER. [L.S.]
